CLAIM

The ornamental design for a cover for fuel dispensing nozzle, as shown and described.

DESCRIPTION

FIG. 1 is a view in perspective of a cover for fuel dispensing nozzle in accordance with the present invention.

FIG. 2 is another view in perspective of the cover for fuel dispensing nozzle.

FIG. 3 is a view in right side elevation of the cover for fuel dispensing nozzle, the broken lines indicating a fuel dispensing nozzle to which the cover is applied, the nozzle forming no part of the design.

FIG. 4 is a view in right side elevation of the cover for fuel dispensing nozzle, the left side elevation being a mirror image thereof.

FIG. 5 is a view in front elevation of the cover for fuel dispensing nozzle.

FIG. 6 is a view in rear elevation of the cover for fuel dispensing nozzle.

FIG. 7 is a view in top plan of the cover for fuel dispensing nozzle; and,

FIG. 8 is a view in bottom plan of the cover for fuel dispensing nozzle.
